UNITED STATES PATENT OFFICE.

BENJAMIN DAHL, OF MINNEAPOLIS, MINNESOTA.

DESIGN FOR A TIRE.

61,033.

Patented June 6, 1922.

Application filed March 20, 1920. Serial No. 367,495. Term of patent 3½ years.

To all whom it may concern:

Be it known that I, BENJAMIN DAHL, a citizen of the United States, residing at Minneapolis, in the county of Hennepin and State of Minnesota, have invented a new, original, and ornamental Design for Tires, of which the following is a specification, reference being had to the accompanying drawing, forming a part thereof.

Fig. 1 is a side elevational view of the tire,

Fig. 2 is a top view of the tire showing my new design,

Fig. 3 is a sectional view of the tread portion of the tire on the lines 3—3 of Fig. 2, and

Fig. 4 is a view partly in elevation, looking at the tire from the side and partly in section, the section being on line 4—4 of Fig. 3.

I claim:

The ornamental design for a tire as shown.

In witness whereof, I hereunto subscribe my name this 18th day of March, A. D. 1920.

BENJAMIN DAHL.
